United States Patent Office.

WALTER BOUND, OF HACKENSACK, NEW JERSEY.

Letters Patent No. 61,601, dated January 29, 1867; antedated January 19, 1867.

IMPROVEMENT IN CARRIAGE CLIPS.

The Schedule referred to in these Letters Patent and making part of the same.

TO ALL WHOM IT MAY CONCERN:

Be it known that I, WALTER BOUND, of Hackensack, in the county of Bergen, and State of New Jersey, have invented a new and useful Improvement in Carriage Clips; and I do hereby declare that the following is a full, clear, and exact description of the same, reference being had to the accompanying drawings, making a part of this specification, in which—

Figure 1 is a side view of a carriage clip, constructed according to my invention.

Figure 2 is a plan or top view of the same.

Figure 3 is a partial transverse section of the same, taken in the line $z z$ of fig. 1.

Similar letters of reference indicate corresponding parts in all the figures.

This invention consists in a novel construction of a clip for connecting the pole or shafts of a carriage with the axle thereof, whereby the said pole or shafts may be attached to or removed from the carriage with great facility, and whereby all liability of the accidental derangement of the clip, and consequent casual disconnection of the pole or shafts from the carriage, is effectually avoided.

To enable others to understand the construction and operation of my invention, I will proceed to describe it with reference to the drawings.

A represents the loop or strap by which the clip is attached to the forward axle of the carriage, the said strap being placed upon the said axle and secured thereto in the ordinary or in any suitable manner. Formed solidly upon one side of the strap A is a flat plate, B, and formed rigidly upon one end of the said plate, and projecting forward at right angles thereto, is an end piece, C; the plate B and rigid end piece C constituting the frame of the clip. Firmly fixed in the end piece C, near the outer extremity thereof, is a cylindrical pin or bolt, D, which projects inward from the aforesaid end piece in front of the plate B, and parallel with the same. E is a hinged end piece, which corresponds in size and shape with the rigid end piece C, and is hinged to the opposite end of the plate B, as shown at a, except when turned aside to allow the attachment or removal of the tongue or the shafts from the carriage. This hinged end piece E is situated opposite the rigid end piece C, parallel with the same, and has a circular socket or recess, b, formed in its inner surface near its outer extremity, the said recess b fitting over the end of the bolt D, when the clip is closed, as shown in fig. 3, and also indicated in dotted lines in figs. 1 and 2. F is a flat spring, the rearmost end of which is fixed to the upper edge of the plate B, at or near the upper end of the hinge a, and which projects forward so that it is situated longitudinally over the uppermost surface of the hinged end piece E, when the clip is closed, as more clearly shown in fig. 1. This spring F has a downwardly projecting lip, c, formed upon its outer edge, and near its outer or forward extremity, which projects down past the outer edge of the upper surface of the said hinged end piece, and holds it firmly in position against the end of the bolt D, as more clearly indicated in fig. 3, while by forcing the spring E upward so that the lip c is brought away from the hinged end piece E, the said end piece may be turned back nearly in line with the plate B, as indicated by the dotted lines in fig. 2, thus uncovering the end of the bolt D. That part of the upper surface of the hinged end piece E which passes under the lip c, in closing the clip, is made bevelled or sloping on its inner edge as shown at d, in fig. 2, in order that the said lip may be forced upward when the said end piece is swung inward, to allow the passage of the same, the said lip being then forced down by the spring F, past the outer edge of the end piece E, to lock the same in a closed position, as hereinbefore fully explained. Iron sockets or ring-headed straps are fixed to the rearmost end of the tongue or shafts in the ordinary or in any suitable manner, and the clips being secured upon the forward axle of the carriage as hereinbefore mentioned, the said sockets are placed upon the bolts D thereof, the hinged end pieces being turned outward to allow the attachment of the said sockets to the said bolts D, or their removal therefrom, the sockets being retained upon the bolts D by the hinged end pieces E, which are firmly held against the ends of the said bolts by the lips b of the springs F, after being turned inward as just set forth, and the outer ends of the bolts being supported against the strain exerted upon them by the draught upon the tongue or shafts by being fitted into the recesses l, when the hinged end pieces are in a closed position as hereinbefore explained.

What I claim as new, and desire to secure by Letters Patent, is—

1. The hinged end piece E, in combination with the bolt D, and frame B C, substantially as herein set forth for the purpose specified.

2. The spring F, provided with the lip c, and applied in relation with the hinged end piece E, bolt D, and frame B C, substantially as herein set forth for the purpose specified.

WALTER BOUND.
